ROBERT T. POLLOCK, OF BOSTON, MASSACHUSETTS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR TREATING HYDROCARBON OIL

Application filed May 12, 1920. Serial No. 380,745.

This invention relates to improvements in a process and apparatus for treating hydrocarbon oils and refers more particularly to a process for converting high into low boiling point hydrocarbons such as gasoline and the like.

Among its salient objects are to provide a process in which the raw oil prior to being introduced to the cracking zone is preheated by being passed through circulating chambers in the dephlegmator thereby relieving the vapors of their heavy oil content and avoiding the objectional feature of mixing the raw oil with the oil vapors which necessarily extracts a part of the low boiling point cuts; to provide a process by means of which a higher percentage of the low boiling point distillates may be recovered and a process which permits of a subsequent combining of the raw oil and higher boiling point reflux to be charged to the cracking zone; to provide an improved type of apparatus for effecting this process and in general to provide a process and apparatus of the character referred to.

In the drawing:

The figure is a diagrammatic elevational view of the apparatus.

Referring to the drawing, the raw oil is charged to the apparatus from any convenient source by pump 1 through the inlet pipe 2 to the circulating chambers 3, 4 and 5 mounted in the dephlegmator 6 which take the form of ducts or hollow partition walls and furnish a means for interchanging the heat of the generated oil vapors to the raw oil and at the same time act as a cooling or condensing agent to said vapor. The raw oil circulates first through the chamber 3, thence through the pipe 7 to the chamber 4 and finally through the pipe 8 to the chamber 5 from which it is drawn off through the line 9 and charged to the heating zone. A valve 10 is interposed in the line 2 and a similar valve 11 in the draw off line 9. The reflux recovered from the dephlegmator is drawn off through the pipe 12 which is controlled by a valve 13 and is then combined with the raw oil which has been preheated in the dephlegmator. The mixture is then

charged to the heating zone. The proportions of raw oil and reflux in this mixture may be controlled by the valves 13 and 11. The raw oil with its reflux content is introduced through the inlet line 14 to the heating tubes 15 which are mounted above a furnace 16 which is preferably heated by means of gas burners 17. The heated oil passes from the heating tubes through the connecting pipe 18 to the vapor chamber 19 where the greater part of the cracking takes place. The vapors released in this chamber rise into the line 20 by means of which they are directed to the lower part of the dephlegmator 6. In the dephlegmator the vapors pass through the risers 21 through the separate stages being subjected to the cooling and condensing effect of the raw oil. Stand pipes 22 control the depth of the pools of reflux which are maintained in separate stages. The reflux overflowing from these stages is drawn off through the line 12 as explained. The uncondensed vapors pass out through the top of the dephlegmator through the goose-neck 23 and are condensed in the coil 24 mounted in the water condenser 25. From the water condenser the distillate is drawn off through line 26 and collected in a suitable receiver in the tail house, not shown. Valves 27, 28 and 29 interposed in the lines 20, 23 and 26 respectively, furnish means for regulating the flow of vapors and liquids in the lines and at the same time a means for controlling the pressures in the different portions of the still.

The operation of the process is as follows: the raw oil is introduced and circulated through the hollow partition walls of the dephlegmator where it is preheated and condenses the higher boiling point fractions of the oil from the oil vapors. This preheated raw oil is then combined with the reflux from the dephlegmator and the mixture charged to the heating tubes where it is raised to a cracking temperature. The oil vapors which are released during the cracking of the oil pass up through the dephlegmator where the higher boiling point fractions are condensed therefrom and are drawn off as reflux. The lower boiling point or lighter fractions pass

over to be condensed and collected as distillate in the receiver. By this process we have an interchanging of a portion of the heat contained in the oil vapors to the raw oil which causes a condensing out of the higher boiling point oil fractions, without the objectionable feature of having the raw oil intimately intermingled with the oil vapors during dephlegmation. Where the raw oil 10 comes into intimate contact with the heated oil vapors there is a consequential absorbing of a certain amount of the lighter fractions by the raw oil and therefore a decreased efficiency in the process.

15 An illustrative run of mid continent gas oil is as follows: Gas oil of approximately 31 or 32° B. is preheated as explained in the dephlegmator and combined with the reflux therefrom. This mixture is charged to the 20 cracking tubes where it is subjected to a heat of about 800° F. The heated oil is then directed to the vapor chamber where it is maintained at a heat of about 700 to 750° F. and the vapors released therefrom. After 25 being dephlegmated in a dephlegmator of this type, a yield of from 50 to 60% pressure distillate having an end point of about 450° F. is obtained.

I claim as my invention:

30 1. A process for cracking hydrocarbon oil comprising subjecting oil to cracking conditions of temperature and pressure in a heating zone, subjecting evolved vapors to a refluxing action by causing the vapors to pass 35 first in heat interchange relation but out of physical contact with a moving body of charging oil for the process and to thereafter pass in intimate physical contact with a body of reflux condensate, and maintaining 40 said body of reflux condensate in heat interchange relation with said moving body of charging oil.

45 2. A process for cracking hydrocarbon oil comprising subjecting oil to cracking conditions of temperature and pressure while flowing in a restricted stream through a heating coil, delivering the heated oil to an enlarged reaction chamber from which no unvaporized oil is permitted to return to said 50 coil, subjecting vapors evolved from the oil to a reflux condensing action by causing such vapors to pass first in heat interchange relation but out of physical contact with a moving body of charging oil for the process, and 55 to thereafter pass in intimate physical contact through a collected body of reflux condensate, maintaining said body of reflux condensate in heat interchange relationship with said moving body of charging oil, and delivering reflux condensate and charging oil 60 from said bodies to said heating coil.

65 3. In combination with an oil cracking apparatus, a dephlegmating column, a plurality of pairs of spaced partition members extending across said column, the space be-

tween each pair of partition members forming a closed passageway, vertical conduits extending through each pair of partition members connecting the portions of the column above and below each pair of partition members, means for flowing oil through the closed passageways formed by said spaced partition members, means for collecting condensate on the upper partition member of each of said pairs of spaced partition members, means associated with certain of said conduits for causing vapors moving therethrough to percolate through the collected condensate on the upper partition member of each of said pairs of partition members, and certain of said conduits being constructed to permit condensate collected in the upper portion of the column to flow downwardly into a body of condensate collected at a lower portion of the dephlegmating column. 85

4. In combination with an oil cracking apparatus, a dephlegmating column, a plurality of pairs of spaced partition members extending across said column, the space between each pair of partition members forming a closed passageway, vertical conduits extending through each pair of partition members connecting the portions of the column above and below each pair of partition members, means for flowing oil through the closed passageways formed by said spaced partition members, means for collecting condensate on the upper partition member of each of said pairs of spaced partition members, means associated with certain of said conduits for causing vapors moving therethrough to percolate through the collected condensate, on the upper partition member of each of said pairs of partition members, and certain of said conduits being constructed to permit condensate collected in the upper portion of the column to flow downwardly into a body of condensate collected at a lower portion of the dephlegmating column, and means for 95 passing condensate from the lower portion of said column to said cracking apparatus. 100

5. In combination with an oil cracking apparatus, a dephlegmating column, a plurality of pairs of spaced partition members extending across said column, the space between each pair of partition members forming a closed passageway, vertical conduits extending through each pair of partition members connecting the portions of the column above and below each pair of partition members, means for flowing oil through the closed passageways formed by said spaced partition members, means for collecting condensate on the upper partition member of each of said pairs of spaced partition members, means associated with certain of said conduits for causing vapors moving therethrough to percolate through the collected condensate, on the upper partition member of each of said pairs of partition members, and certain of 115 120 125 130

- said conduits being constructed to permit condensate collected in the upper portion of the column to flow downwardly into a body of condensate collected at a lower portion of 5 the dephlegmating column, and means for supplying to said cracking apparatus the oil which has passed through said closed passageways and condensate collected in the lower portion of said column.
- 10 6. In combination with an oil cracking apparatus, a dephlegmating column, a plurality of pairs of spaced partition members extending across said column, the space between each pair of partition members forming 15 a closed passageway, vertical conduits extending through each pair of partition members connecting the portions of the column above and below each pair of partition members, means for flowing oil through the closed 20 passageways formed by said spaced partition members, means for collecting condensate on the upper partition member of each of said pairs of spaced partition members, means associated with certain of said conduits for 25 causing vapors moving therethrough to percolate through the collected condensate, on the upper partition member of each of said pairs of partition members, and certain of said conduits being constructed to permit condensate collected in the upper portion of the 30 column to flow downwardly into a body of condensate collected at a lower portion of the dephlegmating column, means for removing condensate from the lower portion 35 of said column, and means for introducing to said cracking apparatus the oil which has passed through said closed passageways.
